UNITED STATES PATENT OFFICE.

CHARLES F. WHITMAN, OF DETROIT, MICHIGAN.

METHOD OF MAKING BOLT BLANKS.

Application filed May 24, 1923. Serial No. 641,080.

To all whom it may concern:

Be it known that I, CHARLES F. WHITMAN, a citizen of the United States of America, residing at Detroit, in the county of Wayne 5 and State of Michigan, have invented certain new and useful Improvements in Methods of Making Bolt Blanks, of which is following is a specification, reference being had therein to the accompanying drawings:

- 10 This invention relates to a method of forming bolt blanks in a four-stage multiple spindle automatic machine, and the method may be conveniently put into practice by making certain alterations in automatic 15 screw machines which produce bolt and screw blanks. With this type of multiple spindle machine it is the present practice to form but a single bolt blank during one cycle of the machine. For instance at one step or 20 stage a blank may be chamfered, advanced to the second stage, and turned down, and advanced to a third stage and cut off. With one blank per cycle of operations, it is necessary to operate the machine at an excessive 25 speed to obtain a high production and the excessive speed racks the machine, necessitates constant adjustment and tension, and causes the machine to rapidly deteriorate.

My invention, in its broadest aspect involves means of forming bolt blanks at a 30 high production rate without excessive speed and wear of the machine, the production rate being eight blanks per cycle or two blanks per each indexing compared to the usual one 35 blank per cycle of operation. To do this turning down, chamfering and cutting off instrumentalities are disposed in and about a four-stage multiple spindle automatic machine so that, at certain stages, two operations may be performed in synchronism, and 40 with the stage operations in sequence and properly timed, a large production of bolt blanks is attainable without racking the machine.

45 My invention will be described by the aid of the accompanying drawings, wherein—

Figure 1 is a plan of a portion of a multiple spindle automatic machine by which my method may be put into practice;

50 Fig. 2 is a cross sectional view of a portion of the machine;

Fig. 3 is a perspective view of a bracket and two holders in proximity thereto;

Fig. 4 is a diagrammatic end view of a spindle carrier explanatory of different stages 55 of production, and

Fig. 5 is a diagrammatic view illustrating the different stages of operation.

As illustrating a machine by which my method may be carried into effect, I have 60 selected some of the parts of a multiple spindle automatic machine which includes a spindle carrier 1 intermittently revolved by a driven shaft 2 and in the spindle carrier are a plurality of driven spindles 3 through 65 which extends pieces of stock temporarily held by chucks 4. The pieces of stock are adapted to be intermittently advanced in the spindles and the protruding ends of the pieces of stock are adapted to be operated 70 upon by chamfering, turning down and cutting off instrumentalities which are movable to and from the pieces of stock. For the purposes of explaining my method I have deemed it unnecessary to illustrate that part 75 of the machine which times or indexes the intermittent movement of the constantly revolving spindles, the advancement of the pieces of stock, and the movement of the various cutting instrumentalities.

80 The machine which I have in mind includes, in addition to the above recited elements, a bed or frame 5 provided with transverse ways 6 for tool slides 7 and 8. On the tool slide 8 is an overhanging bracket 9 having the top thereof provided with ways 10 for adjustable tool holders 11 provided with detachable tools 12 and 13, the tool 12 being used for chamfering or grooving purposes and the tool 13 for cutting off purposes, both 85 of said tools being simultaneously used during the second stage of operations to be hereinafter described.

Under the overhanging bracket 9 is another tool holder 14 provided with a detachable tool 15 which is used for chamfering 90 purposes.

On the tool slide 7 is a tool holder 16 provided with a detachable tool 17 used for cutting off purposes.

Slidable on the shaft 2 is a non-rotatable slide head 18 in which revolves the shaft 2 and adjustable on the slide head 18 are diametrically opposed tool holders 19 each provided with turning down tools, one designated 105 20 and the other 21. The tool holders

are also provided with rotatable stock supporting rolls 22 which follow up the action of the tools 20 and 21 and brace the stock while being operated upon by the tools.

5 The spindles 3 of the spindle carrier are four in number equidistant from the shaft 2, and assuming that the spindle carrier 1 is intermittently rotated in a clockwise direction, as indicated by the arrow on Fig. 4, 10 there are four cessations in the rotative movement of the spindle carrier and such cessations may be considered as stages A, B, C and D where the pieces of stock are operated upon by the tools of all of the tool 15 holders.

At the station A the piece of stock is operated upon simultaneously by the tools 15 and 20, the former chamfering or grooving a piece of stock, as at 23 to form a blank 24 and an embryo blank 25. While the piece of stock is being grooved by the tool 15 the blank 24 is turned down by the tool 20 so that the blank will be complete, but connected to the embryo blank by a neck portion. After these operations the two blanks are advanced to station B where the tools 12 and 13 are simultaneously brought into action, the latter cutting off the first blank as clearly shown in Fig. 5 and the tool 12 25 chamfering or grooving a piece of stock so that the second blank will be in condition to be turned down, which is accomplished after the piece of stock has been shifted to stage C. Upon being turned down by the tool 21 the blank is then shifted to stage D where the tool 17 is brought into action to cut off the second blank.

During the above cycle of operations the pieces of stock are advanced in the spindles 40 when necessary, particularly between stages D and A, and it is apparent that at each stage B and D a complete bolt blank is produced, consequently eight blanks during each cycle of operation or one revolution of 45 the spindle carrier. It is therefore possible to obtain a large production of blanks when the machine is speeded up, but instead of doing this, I prefer to reduce the speed of the machine, compared to machines now in 50 use producing one bolt blank per cycle of operations, and thus prevent racking of the machine, save it from wear and tear, and obviate close attention on the part of a machine operator.

55 I have in mind a small machine in which your bolt blanks may be produced in two stages for small production, and conse-

quently do not care to confine my method of forming bolt blanks or the like to any particular make of machine.

What I claim is:—

1. A method of forming bolt blanks in a four stage multiple spindle automatic machine, which method consists in turning down and chamfering a blank at the first stage; cutting off and chamfering a blank at the second stage; turning down a chamfered blank at the third stage, and cutting off a chamfered and turned down blank at the fourth stage, said operations being carried on in sequence and synchronously so eight blanks are produced in one cycle of the machine.

2. A method of forming bolt blanks in a multiple spindle machine wherein blanks are operated upon different stages and two blanks produced at a time, which method consists in turning down and chamfering a blank at one stage, and cutting off the turned down and chamfered blank and partially forming an embryo blank at another stage.

3. A method of forming bolt blanks in a multiple spindle machine wherein blanks are operated upon, which method consists in two blank chamfering operations, two blank turning down operations, and two blank cutting off operations, said operations being carried on in sequence and synchronously so eight blanks are produced in one cycle of the machine.

4. A method of continuously forming bolt blanks from separated pieces of stock intermittently fed into operative positions and intermittently advanced from one stage to another, which method involves chamfering a piece of stock to form blanks, one of which blanks is turned down during the chamfering operation; advancing the piece of stock to a stage where the piece of stock is again chamfered and the turned down blank cut off; advancing the piece of stock to a stage where the piece of stock is again chamfered and the turned down blank cut off; advancing the piece of stock to another position where the chamfered blank is turned down, and then advancing the turned down blank to a stage where it is cut off.

In testimony whereof I affix my signature in presence of two witnesses.

CHARLES F. WHITMAN.
